SHUTTLE FOR WIRE-WEAVING LOOMS

Chester F. Wickwire, Cortland, N. Y., assignor
to Wickwire Brothers, Inc., Cortland, N. Y., a
corporation of New York

Application April 21, 1949, Serial No. 88,775

5 Claims. (Cl. 139—197)

1

This invention relates to the weaving of wire fabrics and provides a new type of shuttle which, as compared with prior practice, will handle longer continuous strands of weft wire and will permit the loom to be operated at a higher speed and at the same high speed whether the fixed spool in the shuttle is full or nearly empty.

Heretofore the almost universal practice has been to mount a rotary bobbin in the shuttle and provide a trailing or dragging spring which affords the desired tension and also reverses the rotary motion of the bobbin to take up slack when the motion of the shuttle reverses. Since the shuttle must pass out of the shed, the wire would slacken during the initial motion of the shuttle toward and into the newly formed shed after each reversal, except for the provision of means for rewinding the slack on the bobbin. There is a practical limit to the rewinding force that is available. This limits the weight and size of the bobbin which can be operated, and consequently objectionably limits the length of weft wire which can be woven as one continuous strand.

In an effort to overcome this limitation it has been proposed to use a coil of wire which is fixed, so that the disturbing inertia effects of the rotating bobbin will be avoided. However, the prior attempt to use this fixed coil scheme involved unwinding the wire from the interior of the coil and the provision of a take-up mechanism which did not rewind the wire, but instead, accumulated it temporarily on a rotary take-up disk.

While the advantages of the fixed coil are obvious, they have not heretofore been obtained without penalty. So far as is known, the fixed coil scheme of operation, above described, has not enjoyed wide commercial acceptance. Certainly it has not displaced the rotary bobbin scheme of the earlier art.

The present invention uses a fixed coil which is wound in the conventional manner, and from the outer convolution of which the wire is withdrawn. It is withdrawn and controlled by a rotary flyer which swings about the axis of the coil against the frictional resistance offered by a dragging coil spring mechanism. When the shuttle reverses, the dragging coil spring becomes effective to reverse the revolving motion of the relatively light flyer and so cause the flyer to rewind part of the wire back on the coil from which it had just been unwound. This scheme, which has already been demonstrated on a practical basis, has marked operative advantages.

The invention will now be described by refer-

ence to the accompanying drawings which illustrate the pilot embodiment already successfully used.

In the drawings:

Fig. 1 is a plan view of the shuttle with the coil in place and the shuttle threaded.
Fig. 2 is a front elevation of the same.
Fig. 3 is a fragmentary view of the body of the shuttle with the spool removed.

10 Fig. 4 is a perspective view of the spool and the egress guide.

Fig. 5 is a fragmentary plan view of the shuttle body with portions broken away to illustrate the construction of the dragging coil spring mechanism.

15 Fig. 6 is a section on the line 6—6 of Fig. 1 and is drawn on the same scale as Fig. 5.

In the drawings the body of the shuttle is generally indicated by the reference numeral 11 and carries the latch arms 12 whose form and function are familiar to persons skilled in the art. They are the means by which the shuttle is passed back and forth through the shed and their function is unaffected by the present invention.

25 As best shown in Fig. 3 the body 11 comprises a bottom plate 13 in which the dragging coil spring mechanism hereinafter described is housed; an arcuate upstanding wall 14 rising from the base 13 and to which the latch arms 12 are attached; and an inwardly directed arcuate flange 15. A flanged spool 16, best shown in Fig. 4, carries the coil of wire and is sustained in the shuttle body by the upward one of its two flanges. This upward flange rests upon the

30 flange 15 above described and is centered partly by the bosses 17 and partly by two over-hanging lugs 18. It is latched in position by a swinging latch 19 which has a latch finger 21 dimensioned to enter an aperture 22 formed in the upper flange of spool 16 to receive it. As a simple means of retaining the swinging latch in its engaged position use is made of an inserted bow spring 20 shown in Fig. 1. The spool has a central tube 23 and consequently is axially apertured. Its upper end is closed by an annular plug 24 at the center of which an egress guide 25 is mounted.

35 It will be observed that the egress guide is supported by the spool and the spool in turn is supported by the body of the shuttle but in effect the egress guide is supported by the body of the shuttle and is coaxial with the spool. The spool does not rotate but is fixed positively in position.

The bottom plate 13 is recessed at its center 40 and carries a fixed hub 26, the hub being en-

circled by a rotating annulus 27 and the two members 26 and 27 being formed to afford races for an anti-friction bearing which includes the balls 28. The annulus 27 is confined by a retaining plate 29. The retaining plate is removably attached to the bottom plate 13 by screws 31 and overlies both the margin of the annulus 27 and an annular chamber formed in the base plate 13 to receive a dragging coil spring 32. This spring 32 resembles a clock spring. It is attached to the annulus 27 at its inner end as indicated at 33 in Fig. 5. Its outer end is free but is in frictional engagement with the outer wall of the chamber in which it is housed. The area of such frictional engagement is indicated generally by the numeral 34 on Fig. 5.

Obviously if the coil spring tends to expand it will develop friction in the area 34 and the degree of such friction can be determined by choosing the normal configuration of the spring.

Attached to the annulus 27 by screws 35 is the arm 36 of the flyer. As a practical matter the wire guide on the flyer should have one extremity located at the geometrical axis of the spool and the other extremity extending over one flange of the spool so that it over-hangs the coiled wire on the spool to avoid unnecessary friction and to prevent kinking of the wire.

The guiding means takes the form of an inner roller 37 which has a rather deep V-groove and also an outer roller 38 which likewise has a deep V-groove. The roller 37 lies within the tubular core 23 of the spool. The outer roller 38 is skewed so that it will receive the wire strand from the coil between the flanges of the spool, guide it around the margin of the lower flanges of the spool, and deliver it to the inner guide roller 37. The movement of the wire is reversed during rewinding.

In Fig. 2 the coiled wire is generally indicated by the letter A. The unwinding strand B leads over the outer guide 38 and then, as indicated at C, passes parallel to the lower flange of the spool 16 to the guide 37. The part C of the strand is likewise indicated in Fig. 6. The strand leaves the guide 37 and, as indicated at D in Fig. 6, is lead directly to the egress guide 25. This guide is rounded at its exit end so that the wire will not be too sharply bent as it is laid in the shed by the shuttle.

With applicant's device no special winding of the bobbin is necessary. Since the weft tension is controlled solely by the flyer and the drag spring, stability and uniformity of action are assured. The weight of wire on the bobbin has no effect whatsoever on the slack take-up. Since variations in the outside diameter of the wire coil change only the angle of approach of the wire to the outer guide on the flyer, and the rate at which the flyer rotates, and since the mass of the flyer is very low, whatever variations in tension there may be are very much less than those encountered with rotating bobbins, and are tolerable with fixed bobbins of many times the capacity of the old rotating bobbins.

In the prior art fixed coil machine, tension was controlled in distinctly different ways when wire was being drawn off and when slack was being rewound. Because applicant's flyer performs both these functions, and merely rewinds the slack on the coil from which it was unwound, the arrangement here disclosed inherently favors uniformity of tension, whether or

not it attains absolute uniformity. Such lack of uniformity as may exist is not detectable in the final result, i. e. the resulting weave.

The dragging coil spring mechanism has been used in the art to control the bobbin but has never, so far as known, been used to control a flyer. Since the mass of the flyer is uniform and quite low, such springs give a new and greatly improved performance in the new combination. Since the term "dragging coil spring" is well known in the art it will be used in the claims in its generic sense.

Modifications within the scope of the claims are contemplated and the specific construction illustrated is exemplary only.

I claim:

1. A shuttle for wire weaving looms comprising in combination, a shuttle body; a wire-egress guide supported in fixed relation to said body; means for fixedly supporting a coil of wire on said body with its peripheral convolutions exposed; a flyer mounted to revolve relatively to said body on an axis substantially coincident with the axis of said coil, said flyer having a central wire-guide substantially at said axis and arranged to direct wire to said egress guide, and having also a revolving wire-guide which swings in a path encircling said coil as the flyer revolves; and spring means of the dragging coil type, arranged to offer frictional resistance to revolution of the flyer in the direction to unwind wire from the coil, and serving upon release of wire tension to revolve the flyer in the opposite direction and so rewind wire upon the coil.

2. The combination defined in claim 1 in which the wire coil is wound between the flanges of a flanged spool and means are provided to connect said spool releasably with said shuttle body.

3. The combination defined in claim 1 in which the egress guide is located on the axis of the coil and the wire moves between the central guide of the flyer and said egress guide substantially along said axis.

4. The combination defined in claim 1 in which the wire coil is mounted on a flanged spool, said spool is releasably connected with the shuttle body by means engaging one flange thereof and the flyer swings between a portion of the body and the other flange of the spool with its revolving wire-guide overhanging said flange.

5. The combination defined in claim 1 in which the wire coil is mounted on a flanged spool having an axial passage; said spool is releasably mounted on the shuttle body with one flange in engagement with the body; the flyer swings in a plane adjacent the other flange of the spool with its revolving wire-guide overhanging said other flange; and said egress guide is positioned at the end of the axial passage through the spool remote from the flyer.

CHESTER F. WICKWIRE.
